TOY HEEL FOR A SHOE OR THE LIKE

Eddie Feldman, Chicago, Ill.

Application January 27, 1953, Serial No. 23,330

Term of patent 7 years

(Cl. D7—7)

To all whom it may concern:

Be it known that I, Eddie Feldman, a citizen of the United States, residing at Chicago, in the county of Cook and State of Illinois, have invented a new, original, and ornamental Design for a Toy Heel for a Shoe or the like, of which the following is a specification reference being had to the accompanying drawing, forming a part hereof.

Fig. 1 is a side elevational view of a toy heel for a shoe or the like, embodying my new design;

Fig. 2 is a top plan view of the toy heel;

Fig. 3 is an elevational view of the side of the toy heel opposite that shown in Fig. 1.

Fig. 4 is a front elevational view.

I claim:

The ornamental design for a toy heel for a shoe or the like, as shown.

EDDIE FELDMAN.
